SHIPPING CONTAINER

Oliver M. Babcock, Evanston, Ill.

Original application November 11, 1931, Serial No. 574,249. Divided and this application January 11, 1935, Serial No. 1,359

17 Claims. (Cl. 229—23)

This invention relates to shipping containers and more particularly constitutes an improvement over the container shown in my Patent No. 1,704,118, of March 5, 1929. This application is a division of my copending application Serial No. 574,249, filed November 11, 1931, which matured into Patent No. 1,991,071.

Among the objects of my invention are:—
To provide a shipping container that is usually light in weight, rigid, strong and economical to manufacture;

To provide a shipping container that instead of having six separate panels assembled to form a container by nailing along the twelve edges, the body of the container, which is of fibre board or the like, is formed with score lines to permit folding around rigid ends so as to do away with the necessity of further attaching the side walls to the top or bottom walls;

To have the two ends of the foldable body blank meet along a face of the container instead of along one of the edges, thus eliminating the necessity of attaching the meeting parts together along one of the edges of the container;

To provide means whereby the meeting edges of the body blank overlap in such a way that the face of the container on which they meet and overlap is perfectly flat and prevents the entrance into the container of dust and dirt, and also gives additional strength along the meeting edges;

To add reinforcing strips to the wall material and form notches in the ends of said strips to facilitate removal of the fastening nails after the top has been pried open, the reinforcing strips being rigidly secured to the wall material;

To provide an improved type of shipping container made from fibre board, corrugated board, or the like, and reinforced with wood cleats on two faces of the container, and which may or may not have reinforcing strips on one or more of the other faces of the container;

To provide a shipping container that will require less sheet material in its manufacture than is now required in the so-called regular slotted type fibre or corrugated board boxes, which latter are in use in this country to the extent of hundreds of millions per year;

To provide a shipping container that can be shipped in knocked down condition from the box factory to the consumer;

To provide a light, strong and cheap shipping container that can be closed with the nail-in machines and sealing equipment in common use today;

To provide a light, strong shipping container in which the cleats or reinforcing strips, or both, are advantageously located so as to give great protection to the contents of the container at a minimum cost;

To provide a shipping container which in its preferred form has cleated panels on two faces of the container, which cleats provide handholds so as to make it easy, attractive and economical in handling and shipping;

To provide a preferred form of shipping container with which one face can be opened by prying up the nails like in a nailed box, and which on another face may be opened similar to the way the slotted fibre boxes are now opened;

To provide a shipping container which can be economically opened and reclosed for reuse;

To provide a strong, light shipping container which adapts itself advantageously for reuse as a grocer's delivery box or as a handy box in which to store things;

To very considerably decrease the weight of shipping containers without sacrificing strength, and thereby make possible very considerable savings in freight charges;

To utilize material in the making of the cleats and reinforcing strips which are produced from the same class of wood as that from which building laths are made, and which laths sell for considerably less than lumber of similar quality, thereby effecting an economy.

To produce a shipping container of fibre board or other light material, having reinforced end walls, at least some of the walls being constructed to have interlocking relation with adjacent walls to promote strength with unusual lightness;

To so reinforce the wall material of shipping containers as to produce maximum lightness with strength.

Other objects, advantages and capabilities will later more fully appear.

My invention also resides in the combination, construction and arrangement of parts illustrated in the accompanying drawings, and while I have shown therein my preferred form, with modifications, I wish it understood that the same are susceptible of modification and change without departing from the spirit of my invention.

In the drawings:—

Fig. 1 is a perspective view of the preferred form of my shipping container, showing the cover flaps open and the container packed with cylindrical packages.

Fig. 2 is a development of the main sheet of

material, having reinforcing strips rigidly secured thereto, said sheet being provided with scorings whereby it may be folded to form the bottom, two sides and two cover flaps of the container.

Fig. 3 is a perspective view of one of the end panels.

Fig. 4 is a fragmentary perspective detail showing the construction to permit the overlapping joint at the meeting edges of the cover flaps.

Fig. 5 is a perspective view of a completed and closed box of the type shown in Fig. 1.

Fig. 6 is a fragmentary perspective detail showing one of the slotted ends of the reinforcing strips to permit removal of the nails after the cover flap has been pried open.

Fig. 7 is a perspective view of a modified form of container, and showing the several parts slightly separated from each other prior to being secured together to form a completed container.

Fig. 8 is a perspective view of the box whose parts are shown in Fig. 7, but showing the parts in assembled relation, with the near side not yet fastened to the end members and the top being partially open.

Fig. 9 is a perspective view showing the container of Figs. 7 and 8 completed and fastened in closed position.

Fig. 10 is a perspective transverse sectional view through a box similar to that shown in Figs. 7 to 9, but being provided on its interior bottom faces with sheets of veneer, or the like, instead of elongated strips shown in Fig. 7.

Referring more particularly to Figs. 1 to 6 of the drawings, my improved container, as there shown, comprises primarily four integral sides foldably connected together, the fourth or top side being preferably constructed in the form of two cover flaps, each being integral and foldably connected to its adjacent side wall.

The sheet of material from which the integral bottom, sides and cover flaps are made is shown at 1 in Fig. 2. Rigidly secured to the inner face of sheet 1, at suitably spaced distances, are the elongated reinforcing strips 2. Sheet 1 at predetermined positions is transversely scored, as along lines 3, 4, 5 and 6, these scorings being such as to permit sheet 1 to be folded along these lines to form the container sides 7 and 8, bottom 9, and top flaps 10 and 11. In assembling the container sheet 1 is folded around the end wall members 12, which are formed of suitable sheet material, which is reinforced by the marginal cleats 13. Cleats 13 are provided with notches 14 to receive the ends of reinforcing strips 2 when the sheet 1 is folded around these end wall members, as will be readily understood in Fig. 1.

As noted in Fig. 2, the reinforcing strips 2 may be spaced from each other as desired, but at the folding lines 3, 4, 5 and 6 the strips are preferably spaced only a slight distance apart, so that when the fold or bend is made along such lines the adjacent strips will touch each other, or one strip will overlap the other, as shown in the two bottom corners of the near end of Fig. 1. As viewed in Fig. 2, sheet 1 at the right hand end extends at 15 a slight distance beyond the adjacent reinforcing strip 2, while at the left end of said sheet the reinforcing strip 2 extends a slight distance (as indicated at 16) beyond the edge of sheet 1. At its middle portion (or other location desired other than at the side edge of the box) each of the top and bottom cleats 13 of the end walls is provided with an elongated notch 17, which is preferably of a length equal to the com-

bined width of two reinforcing strips. The purpose of this is seen in Fig. 4 to be the provision of overlapping surfaces along the meeting edges of the cover flaps, which greatly strengthens the cover of the container, and also leaves the top of the same flat, which is advantageous both from the standpoint of printing, writing or stenciling on the container cover as well as stacking the containers in piles.

To improve the reuse value of my containers I have provided means to facilitate the removal of nails from the cover flaps, which nails if not removed would be a hazard to anyone working with or around the container. This feature is shown in Fig. 6, in which a notch 18 is provided in each end of each of the strips 2, which are secured to the cover flaps 10 and 11. In nailing the cover flaps to the panel 13 of the ends walls (or solid wood end walls if desired), the nails are driven first through the sheet of wall material of the cover flaps and then through the slots 18 and into the wood of cleats 13 or other end material. As will be readily understood, the head of the nail will straddle slot 18 so that it will bear against the material of the strip on each side of the slot, but will permit easy removal of the nail after the cover flap has been pried open, which would not be true if the nail were forced to form its own hole through strips 2 when being driven.

As shown in Fig. 1, the reinforcing strips 2 are so positioned on sheet 1 that in the finished box these strips will prevent the cans, cartons, or other packaged goods packed in the container from coming in contact with the outer sheet material, thereby avoiding the danger of same damaging the sheet material and at the same time adding rigidity and strength to the container. The integral foldable joints between the bottom, sides and cover flaps eliminate the necessity of nailing these parts together and yet provide great strength between these parts. This very materially cheapens the manufacture of containers, as four sides of the container may be made in one strip (see Fig. 2), and shipped in knocked down condition from the factory to the consumer. All the consumer has to do is assemble the end wall members in position and fold the sheet 1 there-around, and nail the side walls and bottom to the end wall members by nailing machinery now in common use. After the container is packed the top flaps may also be nailed shut in nailing machines or by hand, as desired.

It is thus seen that I have provided a container that may be easily and quickly manufactured and shipped in knocked down condition, readily assembled by the consumer, and while being unusually light in weight possesses very considerable strength, may be readily handled due to the cleats 13 serving as handholds, and which container is not only pleasing in appearance but is readily adapted for reuse either as a shipping container or as a grocer's delivery box or the like.

The modified form of container shown in Figs. 7, 8 and 9 comprises the two side members 20 and 21, to the former of which is integrally and foldably connected the bottom flap 22 and top flap 23, while to said member 21 is integrally and foldably connected the bottom flap 24 and the top flap 25. Each of bottom flaps 22 and 24 have elongated reinforcing strips 2 rigidly secured thereto, the arrangement of the adjacent strips at the meeting edges of the bottom flaps 22 and 24, in the preferred form, being similar to that described above and shown in Fig. 4.

The end wall members 26 are each provided

with an integral foldably connected upstanding flap 27, which, in the preferred construction, are of a height sufficient to enable them to meet at the center of the box when folded downwardly, as suggested in Fig. 8. Suitable scoring lines 28 are provided between flaps 27 and end wall members 26 to facilitate their being folded inwardly during the operation of closing the container. Scorings along lines 29 and 30 are also provided in each of the side wall members 20 and 21 with their integral flaps, to permit said flaps to be folded around the end wall members after the latter have been placed in proper position between the side walls 20 and 21. Notches 14 and 17 similar to those shown in Figs. 1 to 5 are also formed in the bottom of the bottom cleat of each of end walls 26 to receive reinforcing strips 2 of the bottom flaps.

End walls 26 in position between the side walls, and with the bottom flaps folded against the bottom of the end walls, are shown in Fig. 8, except that the near side wall is shown a slight distance away from the edge of the end walls for the sake of clearness. The flap extensions 27 of end wall members 26 in the form of box shown in Figs. 7 and 8 stand higher after assembly than do the top flaps 23, in order that the flaps 27 in an elongated box may meet at the middle without such waste of material as would be occasioned in the so-called regular slotted type fibre or corrugated board boxes. As will be understood, in closing a container of the type shown in Figs. 7 to 9, the end flaps 27, after the box is filled, will be pushed inwardly, as shown in Fig. 8, after which the top flaps 23 and 25 may be pushed downwardly and attached to the end flaps 27 in the same manner and with the same standard and efficient equipment now used in closing the present slotted type of shipping carton which is in general use, or they may be fastened into position by nailing into the cleats 13 of the end walls as desired.

A container similar to that shown in Figs. 7 to 9 is shown in Fig. 10, except that sheets 30a and 31 are substituted for the reinforcing strips 2 by being glued, stapled, or otherwise rigidly secured to the inner faces of the bottom flaps 22 and 24, in such manner that they in conjunction with the bottom flaps will produce an overlapping joint of the type shown in Fig. 4. These reinforcing sheets 30a and 31 may be made of rotary cut lumber, fibre-board, corrugated fibre-board or other suitable reinforcing material as desired.

It is thus seen that I have provided a shipping container of unusually light weight but still of great strength, and one which is cheap to manufacture, pleasing in appearance, can be shipped in knocked down condition, and may be easily and readily reused either for shipping purposes or for delivering or storing any material desired.

Having thus described my invention, I claim:

1. A box having walls formed of sheet material one or more of which walls are strip-reinforced walls and are foldably connected to adjacent walls along the longitudinal corners, the closing wall consisting of flaps integral with and foldably connected to the adjacent walls, a pair of end walls each formed of sheet material and each having wood reinforcing members, the free edges of said flaps meeting in the closing face away from the edges where said flaps are foldably connected to the side walls, the edges of the flaps meeting in overlapping relation.
2. A shipping container comprising an integral elongated sheet of wall material of sufficient length to form a bottom wall, two side walls and

two cover flaps, said sheet having reinforcing strips secured thereto and being folded along predetermined lines to form edges of the container, end wall members around which said sheet is folded and to which it is secured, said flaps meeting in overlapping relation within the face of the cover, and notches in the ends of the strips on the cover flaps whereby nails or the like may be readily removed from the cover flaps when said flaps are opened.

3. A shipping container comprising a hinged cover member of thin wall material having reinforcing strips rigidly secured thereto, said strips being formed with a notch in each end adapted to receive a nail or the like to facilitate removal of the nail after the container is opened.

4. A shipping container comprising a pair of end wall members each provided with marginal reinforcing members firmly secured to the end members as distinguished from the other wall members, an integral sheet of wall material to which are rigidly secured reinforcing strips, said sheet being folded around said end wall members and secured thereto, and notches formed in the marginal edges of said end wall members, in which notches the ends of said strips are seated.

5. A shipping container comprising a pair of sheet material end wall members each provided with marginal reinforcing members, secured to the end wall members as distinguished from the other wall members, an integral sheet of wall material to which are rigidly secured reinforcing strips, said sheet being folded around said end wall members and secured thereto, and cover flaps hingedly connected to said sheet and meeting within the area of the cover in overlapping relation.

6. A shipping container comprising a bottom wall, side walls and cover flaps, integrally and foldably connected and formed of sheet material, said walls and flaps having reinforcing strips rigidly secured thereto, and a pair of end wall members each provided with wood reinforcing members around and to which said wall members are folded and secured.

7. A box having sheet material walls, one or more of said walls being provided with reinforcing members secured to the sheet material, said reinforced walls being foldably connected to adjacent walls along the longitudinal corners, end walls having reinforcing cleats to which the reinforced wall or walls are secured by means of nails or the like, whereby fastening elements may be driven through the ends of the reinforcing members and into the cleat or cleats of the end walls, said box and walls being free from binding wire.

8. A container comprising a pair of sheets each folded to form a portion of a bottom, a side and a portion of a top, those parts forming a portion of a bottom having reinforcing material rigidly secured thereto, end wall members about and to which said sheets are folded and secured, said end wall members each having a sheet material extension foldably connected therewith, said extensions being folded inwardly over the contents of the container after filling, said portions of a top being folded over the folded end extensions and secured in position, the bottom portions forming the cover flaps after the box is inverted and opened.

9. A shipping container comprising a pair of opposite side walls formed of sheet material and each having a flap foldably connected to each of its top and bottom edges, the bottom flaps each having reinforcing strips rigidly secured thereto,

- a pair of wood reinforced end wall members to three sides of each of which the two side walls and bottom flaps are secured, said end wall members each having a flap on its fourth side, each of which last mentioned flaps fold under the top flaps, which four flaps are secured into place.
10. A shipping container comprising a pair of side walls formed of sheet material and each having a flap foldably connected to each of its top and bottom edges, a pair of end walls formed of sheet material and provided with marginal cleats, an adjacent pair of said flaps each having secured to one face a reinforcing member, the reinforcing member on one flap extending a distance beyond the longitudinal edge of the flap, and the reinforcing members on the adjacent flap stopping short of the longitudinal edge of that flap, each of the pair of side walls and its respective flaps being secured to three sides of each of the 15 end walls, whereby the reinforced flaps will meet with a reinforcing member bridging the crack therebetween.
11. A box comprising a pair of side walls formed of sheet material and each having an integral folded flap, each of said flaps having longitudinal reinforcing strips rigidly secured thereto, a pair of reinforced end wall members to which said side walls are attached, the free edge of one of said flaps having a portion of a longitudinal strip extending therebeyond, and the free edge of the other of said flaps extending beyond a longitudinal strip, so that said edges may be brought together with the edge of one flap overlapping the edge of the strip on the other flap, 20 with the free edges substantially abutting, and adjacent strips substantially abutting longitudinally of the box.
12. A box comprising a pair of side members formed of sheet material each having a first flap 25 foldably connected to one edge, and a second flap foldably connected to its opposite edge, each of said second flaps having a sheet of reinforcing material secured thereto, a pair of reinforced end wall members to which said side members and second flaps are secured, said end wall members each having a flap foldably connected thereto, said end wall flaps being folded under said first flaps and secured into place.
13. In a shipping container a pair of opposite 30 separate side walls formed of sheet material, each having an integral flap foldably secured to each of its upper and lower edges, and a pair of opposite rigid separate end walls formed of sheet material and each having wood cleat marginal reinforcement, and each end wall also having a flap foldably secured along its upper edge adapted to interfold with the flaps secured to the upper edges of the side walls when folded into closed position, 35 said walls being secured together in box relation.
14. A shipping container comprising a single
- body sheet of fibreboard, corrugated fibreboard or the like, which is foldable along predetermined edges of the container and forms the longitudinal walls of the container and also forms a pair of foldable flaps, one or more of the said walls being longitudinally reinforced with wood, fibreboard, corrugated fibreboard or the like, a pair of end walls made up of thin sheet material reinforced with wood members secured directly to the end walls and to which wood members the reinforced body sheet is attached with nails, staples or the like, said foldable flaps of said body sheet meeting on a face of one of the walls away from the edges of the container.
15. A shipping container comprising an integral sheet of wall material having reinforcing strips rigidly secured thereto at spaced intervals, said sheet being foldable along predetermined lines to form a bottom wall, two side walls and two top wall flaps, and a pair of end members each formed of sheet material and having wood reinforcing means secured thereto forming part of the end members as distinguished from part of the wall material, and to which wood reinforcing means said bottom, top and side walls are secured.
16. A shipping container comprising a body composed of two sheets of fibreboard, corrugated board or the like, which sheets are foldable along predetermined edges of the container to form the longitudinal walls of the container, one or more of the said walls being longitudinally reinforced with wood, fibreboard, corrugated board or the like, two end walls made up of thin sheet material reinforced with wood members, to which wood members the two reinforced body sheets are attached with nails, staples or the like, the end flaps of said two body sheets meeting on the faces of opposite walls of the container when said two body sheets are folded around the two end members.
17. A box having a pair of opposite side walls formed of sheet material, each of said side walls having an integral top flap and an integral bottom flap, one of the flaps of each of said side walls having reinforcing strips rigidly secured across that portion of its face between its ends, the free edges of the two last mentioned flaps meeting to form a face of the box, a pair of end wall members each provided with wood reinforcing members, 50 each of said end wall members having an integral flap adapted to fold over and coat with the two side wall flaps other than the two having reinforcing strips, whereby the two strip reinforced flaps form one closing face and the other two side wall flaps and the two end wall flaps form the other closing face of the box.

OLIVER M. BABCOCK.
